FEED REGULATING DEVICE FOR
SEWING MACHINESFrank A. Kucera, Chicago, Ill., assignor to Union
Special Machine Company, Chicago, Ill., a cor-
poration of Illinois

Application February 5, 1934, Serial No. 709,859

7 Claims. (Cl. 112—210)

The invention relates to new and useful improvements in a feed regulating device for sewing machines, and more particularly to a feed regulating device which includes a crank shiftable radially of the actuating shaft therefor for varying the throw of a feed bar.

An object of the invention is to provide means which is mounted on and rotating with the shaft, but which is capable of adjustment eccentrically about the shaft for positively shifting the position of the crank pin which imparts the feed throw to a feed bar.

A further object of the invention is to provide means rotating with the shaft for indicating the extent of adjustment and the stitch length which is derived from a set adjustment.

In the drawings—

Figure 1 is an end view of a sewing machine having the improvements applied thereto;

Fig. 2 is a plan view of the parts beneath the cloth plate, with a section of the cloth plate turned to open position so as to expose said parts immediately therebeneath;

Fig. 3 is a perspective view of the regulator cap which shifts the crank pin imparting a feed throw to the feed dog;

Fig. 4 is a face view of said regulator cap;

Fig. 5 is a vertical sectional view through the end of the actuating shaft, the crank pin, the link associated therewith and the regulator cap;

Fig. 6 is a sectional view on the line 6—6 of Fig. 5, the actuating link being omitted;

Fig. 7 is a face view of the regulator cap on an enlarged scale, also showing the crank and the parts associated therewith, with the cap set in a position for the maximum throw of the crank;

Fig. 8 is a view similar to Fig. 7, with the cap shifted so as to bring the crank pin substantially to a position of minimum throw;

Fig. 9 is a plan view of the actuating shaft and the parts carried thereby including a portion of the sleeve carried by the crank pin, and

Fig. 10 is a development of the peripheral surface of the regulator cap showing the gauging groove formed therein for indicating the stitch lengths.

The invention is applied to a sewing machine having a feeding mechanism which includes a feed bar movable back and forth for imparting a feed throw to a feed dog. The feed bar is connected to a feed rocker, and the feed rocker is oscillated by an arm which is connected through a link to a crank mounted for radial adjustment in the slot carried by the disk on the

end of the actuating shaft. Associated with this disk is a regulator cap which is provided with a spiral slot in the face thereof, and the crank pin extends through this slot. The slot is of such width that when the regulator cap is shifted, after the crank pin has been released, it will positively shift said crank pin in the radial slot. This regulator cap has grooves formed therein at proper intervals to indicate the stitch length which is produced when the cap is shifted to a certain predetermined position relative to the actuating shaft. Fixed to the actuating shaft is a gauge finger having a zero setting groove relative to which the regulator cap is shifted.

Referring more in detail to the drawings, the invention is shown applied to a sewing machine which includes a supporting bed 1 carrying a standard 2 on which is mounted an overhanging arm carrying a needle head 3. A needle bar 4 is mounted for reciprocation in the needle head. Said needle bar 4 carries a needle 5. Mounted on the bed 1 is a work support 6. Said work support 6 is provided with a section 7 (see Fig. 2) which is mounted on a hinge rod indicated at 8.

The material is fed across the work support by a feed dog 9 carried by the feed bar 10. The feed bar 10 is pivoted at 11 to a feed rocker 12. The feed rocker is mounted for oscillation on a supporting bar 13. The feed rocker is oscillated by means of an arm 14 which is fixed to a pin 15 carried by the feed rocker. The arm 14 at its outer end is connected to a link 16. Said link has a pivotal connection to the arm indicated at 17. The link cooperates with a sleeve 18 carried by a crank pin 19. This crank pin 19 is provided with a headed portion 20 which is mounted in a slot 21 formed in a disk 22 which is fixed to the main actuating shaft indicated at 23.

Surrounding the disk 22 is a regulator cap 24. Said regulator cap 24 is provided with a portion 40 extending over the disk 22, and also a front portion 24a which overlies the front face of the disk 22. There is a slot 25 formed in this front face 24a. The crank pin 19 passes through this slot and then extends through the sleeve 18. Mounted on the crank pin 19 is a washer 19a. This washer lies between the regulator cap and the disk on the end of the shaft which carries the crank pin. One side of the washer 19a is concentric with the inner surface of the peripheral portion 50 of the regulator cap. The washer is held from rotating about the crank pin by a retaining pin 19b which is threaded into the headed portion 20 of the crank pin. A nut 26 is threaded onto the outer end of the crank pin. This nut engages 55

a washer 27 which overlies the sleeve 18. When the nut is turned, it will force the sleeve against the front face of the regulator cap and force the regulator cap against the washer 19a, and 5 the washer against the front face of the disk carrying the crank pin. The headed portion 20 of the crank pin will, of course, be drawn against the inner wall of the guiding slot therefor, and this will clamp the crank pin in a set position. 10 When the nut is released, then the crank pin is released for adjustment. The width of the slot 25 is substantially the same as the diameter of the crank pin. This slot is in spiral form, with one end thereof nearer the center of the 15 disk 22 than the other end. When the nut 26 is loosened and the regulator cap shifted, it will forcibly shift the crank pin in the radial slot in which it is mounted to a different set position in said slot. In other words, by shifting this regulator cap, the eccentricity of the crank pin may be positively varied. The peripheral surface of this regulator cap is provided with a series of spaced grooves extending lengthwise of the cap. These grooves are indicated at a, b, c, etc. Fixed 20 to the disk 22 is a gauge finger 28 provided with a groove or slot 29 in its outer end. When the groove b is brought into alignment with this groove 29 in the gauge finger, the crank pin is set at the proper eccentricity in order to produce 25 a throw in the feed dog that will space the stitches so that there will be three and one-half stitches per inch. If the nut 26 is released and this regulator cap shifted while the main actuating shaft is held from movement so that the 30 groove a is brought into alignment with this groove 29 in the gauge finger, then the crank pin is shifted to a different set position through contact with the side edges of the spiral slot in said regulator cap. When in this set position, 35 then the crank pin has the proper eccentricity for imparting the throw to the feed dog which produces three stitches per inch. If this regulator cap is shifted to bring the groove c into alignment with the groove 29, then four stitches 40 per inch will be produced, and likewise by shifting this regulator cap when the nut 26 is released, the crank pin may be shifted to the proper eccentricity for producing the desired stitch length which will be indicated by the graduations on 45 this regulator cap. After the proper setting of the crank pin has been accomplished, then the nut 26 is turned so as to lock the regulator cap and the crank pin in the desired set position.

It will be apparent from the above that the 50 section 7 of the cloth plate may be readily moved to open position, giving access to the nut 26 and the regulator cap. The operator holds the shaft from turning and loosens the nut 26, and then while the shaft is held from rotation, with the 55 gauge finger in proper position to be viewed, the regulator cap is shifted to the stitch length which is desired to be obtained. This will positively force the crank pin radially of the disk 22 to a set position to give the desired stitch length.

It is obvious that minor changes in the details of construction and the arrangement of the parts may be made without departing from the spirit of the invention as set forth in the appended 60 claims.

Having thus described the invention, what I claim as new and desire to secure by Letters Patent, is—

1. In a sewing machine, the combination of a 65 feed dog, a feed bar carrying said feed dog, a

feed rocker to which said feed bar is connected, an actuating shaft, means operated by said actuating shaft for oscillating said feed rocker, said means including a crank pin carried by and adjustable radially of said shaft, cam means carried by and movable circumferentially about the axis of said shaft for positively shifting said crank pin to different predetermined set stitch length positions, and means for locking said crank pin in a set position. 10

2. In a sewing machine, the combination of a feed dog, a feed bar carrying said feed dog, a feed rocker to which said feed bar is connected, an actuating shaft, means operated by said actuating shaft for oscillating said feed rocker, said means 15 including a disk carried by said actuating shaft, a crank pin carried by said disk and adjustable radially thereof, and cam means carried by the disk and shiftable circumferentially about said disk for shifting the crank pin on said disk to 20 different predetermined set stitch length positions.

3. In a sewing machine, the combination of a feed dog, a feed bar carrying said feed dog, a feed rocker to which said feed bar is connected, an actuating shaft, means operated by said actuating shaft for oscillating said feed rocker, said means including a disk carried by said shaft, a crank pin mounted on said disk for adjustment 25 radially thereof, a regulator cap enclosing said disk and having a spiral slot in the face thereof through which said crank pin extends, said slot being dimensioned and shaped so that when said regulator cap is shifted on said disk it will positively shift said crank pin to different predetermined set stitch length positions. 30

4. In a sewing machine, the combination of a feed dog, a feed bar carrying said feed dog, a feed rocker to which said feed bar is connected, an actuating shaft, means operated by said actuating 40 shaft for oscillating said feed rocker, said means including a disk on said shaft having a radial T-slot therein, a crank pin having a T-head fitting in said slot, a sleeve on said crank, a regulator cap having a portion extending over said disk 45 and a front portion engaging the front face of said disk, said front portion having a spiral slot formed therein through which said crank pin extends, said sleeve being adapted to bear against said front face of the regulator cap, a nut adapted to be threaded onto said crank pin for securing said crank pin and said regulator cap in set positions, said regulator cap having indicating marks on the periphery thereof, and a gauge finger carried by said disk for 50 indicating set positions of the cap whereby said cap may be turned for shifting said crank radially of the actuating shaft to different predetermined set stitch length positions.

5. In a sewing machine, the combination of a 55 feed dog and devices for imparting back and forth and rising and falling movements thereto including a rotary shaft, means for varying the extent of back and forth movement of said feed dog including a crank pin carried by said shaft, 60 said crank pin being adjustable radially thereof and devices shiftable circumferentially about the axis of the shaft for adjusting said crank pin to different set radial positions and means forming a part of said crank pin for securing said 65 crank pin and the adjusting means therefor rigidly in adjusted position.

6. In a sewing machine, the combination of a feed dog and devices for imparting back and forth and rising and falling movements thereto 70

5 including a rotary shaft, means for varying the extent of back and forth movement of said feed dog including a crank pin carried by said shaft, said crank pin being adjustable radially thereof and devices for adjusting said crank pin to different set radial positions, a gauge finger and indicating marks on the adjusting means for indicating the set positions of the crank pin and means forming a part of said crank pin for securing said crank pin and the adjusting means 10 therefor rigidly in adjusted position.

10 7. In a sewing machine, the combination of a feed dog, a feed bar carrying said feed dog, a

feed rocker to which said feed bar is connected, an actuating shaft, means operated by said actuating shaft for oscillating said feed rocker, said means including a crank pin carried by and adjustable radially of said shaft, cam means carried by and rotating with said shaft for positively shifting said crank pin to different predetermined set stitch length positions, means for locking said crank pin in a set position and means rotating with said crank pin for indicating in stitched 10 lengths the set position of the crank pin. 5
